United States Patent Office

Des. 201,544
Patented July 6, 1965

201,544

TOP OF A TELEPHONE BOOTH

Jesse B. Brooks, 5050 Northland Drive NE.,
Atlanta, Ga.

Filed May 14, 1964, Ser. No. 79,983

Term of patent 14 years

(Cl. D13—1)

FIG. 4

FIG. 3

FIG. 1 is a view in perspective of a top of a telephone booth embodying the instant invention;

FIG. 2 is a front view thereof;

FIG. 3 is a side view of the top of a telephone booth shown in FIG. 1; and

FIG. 4 is a top view of said structure.

I claim:

The ornamental design for the top of a telephone booth, as shown.
